CLAIM

The ornamental design for a satellite navigation receiver as shown and described.

DESCRIPTION

Satellite navigation receiver

1.1 is a front isometric view of a satellite navigation receiver;

1.2 is a bottom view thereof;

1.3 is a rear view thereof;

1.4 is a top view thereof;

1.5 is a left side view thereof;

1.6 is a left side perspective view thereof; and

1.7 is a right-side perspective view thereof.

The right and left sides of the satellite navigation receiver are identical; the broken lines illustrate portions of the satellite navigation receiver that form no part of the claimed design.

1 Claim, 7 Drawing Sheets
